[57] CLAIM

The ornamental design for a lawn and garden sprayer,
substantially as shown and described.

DESCRIPTION

FIG. 1 is a perspective view taken from the top, front
and left side of a lawn and garden sprayer showing my
new design;

FIG. 2 is a front elevational view thereof;

FIG. 3 is a perspective view taken from the top, front
and right side thereof; and

FIG. 4 is a top plan view thereof.
